PLASTIC FREEZER SPACER

Raymond E. Sullivan, Wichita, Kan., assignor to
SFB Plastics, Inc.

Filed July 26, 1973, Ser. No. 382,825

Term of patent 14 years

Int. Cl. D9—03; D15—07
U.S. Cl. D15—89

FIG. 1

FIG. 2

FIG. 3

FIG. 4

FIG. 1 is a perspective view of a plastic freezer spacer showing my new design, the pattern is understood to repeat uniformly across the length and width of the circumscribed area;

FIG. 2 is a fragmentary sectional view thereof taken along line 2—2 of FIG. 1;

FIG. 3 is a fragmentary top plan view thereof;

FIG. 4 is a fragmentary perspective view thereof rotated 180° from the position shown in FIG. 1.

I claim:

The ornamental design for a plastic freezer spacer, as shown and described.
